UNITED STATES PATENT OFFICE.

LEWIS H. JOHNSON, OF MADISON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed August 21, 1923. Serial No. 658,512.

To all whom it may concern:

Be it known that I, LEWIS H. JOHNSON, a citizen of the United States of America, residing at Madison, in the county of Morris, State of New Jersey, have invented certain new and useful Improvements in Telephone-Exchange Systems, of which the following is a full, clear, concise, and exact description.

10 This invention relates to an exchange system and more particularly to a system in which connections are established between subscribers' lines by means of automatic selector switch mechanism.

15 In large exchange areas comprising a number of offices, certain of the offices may be remotely removed from each other. Where offices are located in the same district of the area, direct trunking facilities 20 between the offices so located is desirable and economical. If, however, offices are quite remote from each other, as certain of them would be in a large area, the provision of direct trunking facilities of sufficient 25 capacity to handle the peak load would not be economical since the cables would be long and during a large portion of the time, particularly at night, would be employed at only a small percentage of their capacity.

30 One method of routing inter-office connections in large machine switching areas between remotely located offices has been proposed. This proposal employs an intermediate office as a tandem point. Thus, 35 the connection between two remote points A and C would first be built up from point A to B and then treated at B as a connection initiated at that point and built up from B to C. This is accomplished by setting up a complete office and line designation of the wanted line in a central office 40 sender at point A, extending the connection to point B under the control of the sender in accordance with the office designation of 45 the line, then transferring the complete office and line designation from the sender at point A to a register sender at point B.

The sender at point B then controls the setting of switches thereat to extend the connection to the point C and to the wanted line terminating at that point. This invention has been disclosed in one of its as-

pects in the copending application of W. L. Dodge, Serial No. 482,189, filed June 22, 1920.

55 Another method of accomplishing inter-office trunking in accordance with the present invention obviates the necessity of transferring the sender setting from the originating point to the intermediate point by establishing a connection directly from the district selector frame of the originating point to the office selector frame of the intermediate point, the office selector of the intermediate point being then directly controlled by the sender at the originating point to extend the connection to the point in the exchange area where the wanted line terminates. Thus, the district selector of the originating point and the office selector 60 of the intermediate point operate conjunctively in accordance with the office designation of the wanted line.

65 In order, however, that the utmost economy in cable investment may be realized, it is desirable that the office selector of the intermediate point to which the district selector of the originating point has access be arranged for operation over a two wire interoffice loop rather than over the three-wire circuit customarily employed between 70 district selector and office selector frames.

75 It is, therefore, an object of the present invention to provide an office selector which may be controlled either locally from a sender in the same office therewith or remotely from a sender in a distant office, 80 efficiently and economically.

85 It is a further object of the invention to provide means for extending connections between remote offices of an exchange area with the greatest possible economy of trunking and apparatus facilities.

90 It is a further feature of the invention to provide means individual to a selector switch for changing the resistance of the control circuit thereof during different stages of the 95 operation of the switch.

100 These and other objects of this invention are accomplished by providing an office selector, all of the functions of which may be controlled over two-wire trunk-loops leading thereto and therefrom, provision being made to automatically advance the selector

and restore it upon its failure to function in response to the ordinary control within a predetermined period.

It is thought that the invention will best be understood from a consideration of the circuits in detail and the manner in which they function. Referring to the drawings, Fig. 1 shows the line of a subscriber A terminating in an originating office V of the exchange area, the schematic representation of a line switch and sender selector by means of which the line may become associated with a central office register sender, such portions of a register sender shown in the lower portion of Fig. 1 as are necessary to an understanding of the invention and the schematic representation of a district selector by means of which the line may be further extended. Above the dotted line in the upper portion of Fig. 1 the line of a second subscriber D, line switch, district selector and sender of another office W of the exchange area are also indicated.

Fig. 2 shows a two-wire office selector forming the basis of the present invention. This selector is shown as located at an office X intermediate of the office V of Fig. 1 and the terminating offices Y and Z of Fig. 3.

Fig. 3 shows schematically above the dotted line, the switching apparatus of a full mechanical office Y in which the line of the subscriber B terminates, and below the dotted line a plug ended trunk circuit of the manual office Z in which the manual subscribers line C terminates. This manually controlled trunk circuit is arranged for operation on a call indicator basis and functions with the call indicator shown in Fig. 4.

Fig. 4 shows as much of a relay call indicator mechanism for functioning in conjunction with the trunk circuit of Fig. 3 as is necessary to an understanding of the invention.

For a complete disclosure of the invention, the several figures of the drawing should be arranged with Fig. 2 at the right of Fig. 1, Fig. 3 at the right of Fig. 2 and Fig. 4 beneath Fig. 3 with the lines extending to the margins of the several figures in alignment.

The selector switches and office senders indicated in Fig. 1 and the upper portion of Fig. 3 may be of identically the same type and function in the same manner as the similar apparatus disclosed and described in detail in the Patent No. 1,505,171, issued to F. A. Stern, August 19, 1924. Only such portions of these switches and senders have been disclosed herein as are considered necessary to an understanding of the invention, reference being made herein to the above identified patent for a full detailed disclosure.

The selector switch shown in Fig. 2 may be of the general type disclosed in the patent

to E. B. Craft and J. N. Reynolds, No. 1,123,696, issued January 5, 1915, being arranged, however, to be controlled over a two-wire trunk loop. The manually controlled trunk circuit of Fig. 3 and the call indicator mechanism of Fig. 4 may be of the general type shown in the Patent No. 1,464,084, issued to A. E. Lundell and E. H. Clark, August 7, 1923. Only such portions of the call indicator circuits have been disclosed herein as are necessary to an understanding of the invention.

The apparatus to be employed having now been described in a general manner, it will now be assumed that the subscriber whose line is indicated at A of office V, Fig. 1, desires a connection with a subscriber's line B in the full mechanical office Y, Fig. 3, and no direct trunking facilities existing between these offices, it is necessary to route the connection through the office selector of the intermediate office X. The subscriber A upon initiating the call removes his receiver from the switchhook, thereupon causing the setting of the brushes of the line switch 101 upon a district selector link terminating in a district selector 102. When the district link circuit is seized by the line switch, the sequence switch associated therewith (not shown) advances to position 2 in which the sender selector SS functions to associate an idle sender with the subscriber's line. It will be assumed that the sender shown in the lower portion of Fig. 1 is idle and becomes associated with the calling line, whereupon a pulsing circuit is established from battery through the pulsing relay 108, wiper 107, the lower right contact of cam 104, the lower brush of line switch 101, over the subscriber's line loop, returning over the upper brush of switch 101, the lower contact of cam 103, wiper 105 to ground through balancing coil 106. As soon as this pulsing circuit is established, the calling subscriber receives the usual dialing tone and proceeds to dial the digits of the wanted line designation, thereby setting the registers of the sender to record the office and line designations of the wanted line.

As soon as the idle sender becomes associated with the district line, the sequence switch associated with the district link advances to position 3 establishing the usual fundamental circuit from the control relay (not shown) of the district selector through the winding of the sender stepping relay 116. Under the control of the office code registers of the sender, the district selector 102 is set in the well known manner to select the trunk group extending to the intermediate office X, it being assumed that it is necessary to extend the connection through this intermediate office in order to reach the terminating office Y in which the wanted line terminates. Following the selection of the

- proper trunk group, the district selector 102 functions to select an idle trunk in the group such as the one indicated at 109, 110. As soon as the district selector terminates its 5 trunk hunting operation, the sequence switch associated with the district link advances in the well known manner to position 10 whereupon a fundamental circuit is established over the conductors of the inter-office trunk 10 for controlling the office selector 250 at the office X. This fundamental circuit may be traced from battery, the right contact of cam 201, winding of control relay 202, lower contact of cam 203 compensating resistance elements 204 and 205, the lower left and upper right contacts of cam 206, outer right back contact of relay 207, conductor 109, uppermost brush of switch 102, lower contact of cam 111, wiper 112, cam contact 15 113 of the sender control sequence switch 114, lower contact of cam 115, winding of sender stepping relay 116, back contact of the 0' counting relay 117, lower contacts of cam 118, associated with the office sender 20 sequence switch (not shown), contact of cam 119, wiper 120, right contact of cam 121, lower brush of switch 102, trunk conductor 110, inner right back contact of relay 207, upper left and lower right contacts of cam 208, compensating resistance elements 209 and 210 to ground at the left contact of cam 211.
- Stepping relay 116 of the sender and control relay 202 of the office selector operate in this circuit, relay 202 in closing a circuit over the lower contact of cam 212, to battery through the left winding of relay 213, and the stepping relay 116 of the sender preparing the usual control circuits for controlling office brush selection in accordance with the setting of its office code registers. Relay 213 upon energizing locks in a circuit extending through its left winding, left armature and front contact, upper left contact of cam 212 to ground at the armature contact of relay 202. At its right armature and front contact, relay 213 completes a circuit extending over the lower left contact of cam 214 to battery through the magnet winding of sequence switch 200 for advancing the sequence switch into position 2. With the sequence switch 200 in position 2 and relay 213 energized, a circuit is established for the updrive magnet 215 extending 45 from battery through the winding of this magnet, the lower right contact of cam 216 to ground at the right armature and front contact of relay 213. The brush shaft is thereupon driven upwardly in its brush selection movement. As it approaches its first brush selection position, the shaft wiper 217 engages the lowermost conducting portion of commutator segment 218 whereupon a circuit is closed in shunt of the winding of 50 the sender stepping relay 116, which shunt circuit may be traced from battery, right contact of cam 201, winding of relay 202, right contact of cam 203, conductor 219, segment 218, wiper 217, thence to ground at the lower right contact of cam 220. Up- 70 on the establishment of this shunt circuit, the sender stepping relay deenergizes and in the well known manner causes the operation of a pair of counting relays.
- As the brush shaft continues its upward 75 movement, the wiper 217 encounters a non-conducting portion of commutator segment 218 and the previously traced shunt circuit is opened, again permitting the energization of relay 116. Thus, as the brush shaft 80 continues to advance, the stepping relay 116 is intermittently shunted until the sender is satisfied with respect to its office brush registration whereupon the 0' counting relay 117 energizes, opening the fundamental circuit, 85 permitting the deenergization of relays 116 and 202. At the office sender, preparation is thereupon made for controlling office group selection. At the office selector, relay 202 following the opening of its circuit at 90 the office sender is maintained energized over the shunt circuit previously traced until the shaft wiper 217 engages the next non-conducting portion of the commutator segment 218, when the selected brush set will be accurately positioned for tripping upon the subsequent upward movement of the switch shaft. As soon as the shunt circuit is opened at the commutator segment 218, relay 202 deenergizes, opening the locking circuit 100 of relay 213, which thereupon deenergizes, opening the circuit of updrive magnet 215 to arrest the upward movement of the switch shaft. At the back contact of its right armature, relay 213 establishes a 105 circuit over the upper left contact of cam 214 for advancing sequence switch 200 out of position 2 into position 3.
- When sequence switch 200 is in position 3 and the office sender prepared for controlling office group selection, the previously 110 traced fundamental circuit is again established through the windings of relays 116 and 202, relay 202 again establishing the circuit for relay 213, which locks as before. With the sequence switch in position 3 and before it is advanced to position 4 by the energization of relay 213, a circuit is established for the trip magnet 221, extending 115 from battery through the winding of this magnet to ground over the upper right contact of cam 211. When, thereafter, sequence switch 200 advances to position 4 under the control of relay 213, the circuit of updrive magnet 215 is established as before described 120 and the switch shaft is again driven upwardly. The trip magnet 221 causes the tripping of the selected set of brushes.
- As the switch shaft continues in its upward movement, the wiper 222 engages the 125

lowermost conducting portion of commutator segment 223, whereupon, a circuit is closed in shunt of the sender stepping relay 116 which may be traced as before through 5 the winding of relay 202, upper left contact of cam 203, conductor 224, segment 223, wiper 222, upper contact of cam 216 to ground at the right armature of relay 213. The sender stepping relay 116 thereupon 10 deenergizes, causing the operation of a pair of counting relays at the sender in the well known manner. Upon the continued movement of the brush shaft, the wiper 222 engages a non-conducting portion of commutator 15 223, and the shunt circuit is opened, permitting the reenergization of relay 116. Thus, as the switch shaft continues in its upward movement the stepping 116 is intermittently operated until the sender is satisfied with respect to its office group selection 20 registration, when the counting relay 117 operates, opening the fundamental circuit and releasing relay 116. Relay 202 is, however, maintained energized over the shunt 25 circuit through the commutator segment 223 until the selected brush set has been moved to a position in which it engages the first set of terminals in the selected group. When this position is reached, the shaft 30 wiper 222 engages a non-conducting portion of segment 223 and relay 202 thereupon deenergizes. When relay 202 deenergizes, the holding circuit of relay 213 is opened and the circuit of updrive magnet 215 is in turn 35 opened at the front contact of relay 213. With relay 213 deenergized, a circuit is established over the upper left contact of cam 214 for advancing sequence switch 200 out of position 4 into position 5. 40 With sequence switch 200 in position 5, relay 213 becomes energized over its right winding and the upper right contact of cam 228, and at its right armature and front contact closes the circuit over the lower 45 left contact of cam 214 for advancing sequence switch 200 into position 6. If the first trunk of the selected group is idle, relay 213 deenergizes as soon as sequence switch 200 leaves position 5 1/4. If, however, 50 the first trunk is busy, relay 213 becomes locked in position 5 of sequence switch 200 over its left winding, left armature and front contact, lower right contact of cam 231, overflow segment 246 of the switch 55 commutator, shaft wiper 247, test brush 230 and thence to ground on the test terminal of the first trunk. Thus when sequence switch 200 advances into position 6, relay 213 is maintained energized and a circuit 60 is therefore established for the updrive magnet 215 extending over the lower right contact of cam 216 to ground at the right armature and front contact of relay 213. Upon the energization of the updrive magnet 215, 65 the switch shaft is driven upwardly in search of the terminal of an idle trunk in the selected group. As long as the test brush 230 engages the test terminals of busy trunks, relay 213 is maintained energized, but as soon as an idle trunk is encountered 70 the holding circuit of relay 213 is opened at test brush 230 and relay 213 deenergizes, opening the circuit of the updrive magnet 215 and arresting the upward movement of the switch shaft. Until the brush set is 75 properly centered on the terminals of the selected idle trunk, relay 213, is maintained energized over the upper contacts of cam 232, conductor 263, commutator segment 226, shaft wiper 227, upper contact of cam 216 to ground at the right armature and front contact of relay 213. Upon the deenergization 80 of relay 213 a circuit is closed at its right armature and back contact over the upper left contact of cam 214 for advancing sequence switch 200 into the selection beyond position 7. Relay 213 also at the back contact of its left armature places busy ground potential on the test terminal of the selected trunk over the brush 230, shaft wiper 247, 85 commutator segment 246, lower right contact of cam 231, left armature and back contact of relay 213, to ground at the lower left contact of cam 220. As soon as sequence switch 200 advances into position 6 3/4, this busy 90 ground potential is supplied independently of the relay 213 over the upper right contact of cam 220. 95 While the sequence switch 200 was in position 5 a circuit was established from battery through the winding of relay 207, the lower left contact of cam 201, winding of relay 202, lower contact of cam 203, winding of polarized marginal relay 233 to ground at the upper left contact of cam 220. The current flowing through the winding of relay 233 is in a direction which will 100 not operate relay 233 but places it in condition to withstand currents on which it must not operate during the control of the 105 setting of the remaining selector switches employed in the establishment of the connection. Relays 207 and 202, however, operate in this circuit and are locked over a circuit traced through their windings, thence 110 through resistance 234 to ground at the armature and contact of relay 202, as soon as sequence switch 200 reaches position 6. This locking circuit is maintained through 115 the selection beyond position 7. With relay 207 energized the fundamental circuit is extended from trunk conductors 109 and 110 to the incoming selector 350, the tip side of the fundamental circuit being traced from conductor 109, the outer right armature and front contact of relay 207, the lower left 120 and upper right contacts of cam 208, compensating resistance element 210, the upper left and lower right contacts of cam 235, brush 236, conductor 237, the lower contact 125 130

of cam 300, resistance element 301, the right contacts of cam 302 to battery through the winding of control relay 303 of the incoming selector. The ring side of the fundamental circuit may be traced from conductor 110 through inner right armature and front contact of relay 207, the upper left and lower right contacts of cam 206, resistance element 204, the winding of relay 233, the right contacts of cam 238, brush 239, conductor 241, upper contact of cam 304, resistance element 305 to ground at the lower contact of cam 306. The stepping relay 116 of the sender and the control relay 303 of the incoming selector operate in this circuit. The current flowing through polarized relay 233 is not in the proper direction to cause its operation.

Under the control of the sender, the brushes of the incoming selector 350 are set to select a final selector 360 having access to the terminals of the wanted line B. Following the setting of the incoming selector, the sequence switch associated therewith, not shown, advances to the selection beyond position 8, whereupon the fundamental circuit is extended for controlling the setting of the final selector switch 360. During the setting of the final selector, the control relay 303 of the incoming selector is maintained energized over a circuit which may be traced from battery through its winding, the lower contacts of cam 302, the armature and contact of relay 303, the lower right contact of cam 309, lower brush 308 of switch 350 to ground through the left contacts of cam 307. As soon as the last selection is completed at the final selector 360 and the brushes thereof are set upon the terminals of the wanted line, the sequence switch associated with the final selector advances beyond position 8½, thereby opening the circuit of relay 303. Relay 303, upon deenergizing advances the sequence switch of the incoming selector into position 9 in the well known manner. With this sequence in position 9, conductors 237 and 241 are reversely connected to battery and ground for the purpose of advancing the sender at the originating office into the talking selection position. Ground is connected to conductor 237 over the lower contact of cam 300, resistance element 301, contacts of cam 310 and through the lower contacts of cam 311, and battery is connected to conductor 241 over the upper contact of cam 304, resistance element 305, lower contacts of cam 312 and through relay 303. Upon the advance of the sender, talking selection is controlled at the district selector 102 in the well known manner.

This reversal of current in addition to advancing the sender and district link, causes the energization of polarized relay 233 at the office selector 250. Relay 233

upon energizing places a shunt around the winding of relay 202 which may be traced from the right terminal of relay 202 over the upper contact of cam 201 to ground at the armature and contact of relay 233. Relay 202 thereupon deenergizes but relay 207, however, is maintained energized over the left contacts of cam 201 to ground at the armature and contact of relay 233. As soon as the sender advances from the units selection position preparatory to controlling talking selection, the fundamental circuit is opened permitting the deenergization of relays 233 and 303. Relay 233 thereupon opens the holding circuit of relay 207. With relay 207 deenergized, trunk conductor 109 is connected over the outer right armature and back contact of relay 207 through the right winding of relay 240, the lower contacts of cam 235, brush 236, conductor 237, the lower contact of cam 300, resistance element 301, the right contacts of cam 302, the sequence switch of the incoming selector 350 having advanced to position 10 upon the deenergization of relay 303, thence to battery through the winding of relay 303. Truck conductor 110 is also connected over the inner right armature and back contact of relay 207 through the left winding of relay 240, the upper contacts of cam 238, brush 239, conductor 241, upper contact of cam 304, resistance element 305 to ground at the lower contact of cam 306.

As soon as talking selection is started at the district selector 102, the pulsing circuit over wipers 105 and 107 of the sender selector is opened, and following the completion of talking selection, the selected office sender is entirely disassociated from the established connection. The sequence switch of the district selector then establishes a talking circuit over the contacts of cams 111 and 121. At this time, the trunk conductors 109 and 110 are joined at the district selector over the upper contact of cam 111, through the windings of relay 122 and the lower contact of cam 121, thereby completing the circuit previously traced through the windings of relay 240 and the winding of relay 303 at the incoming selector. Relay 303 energizes in this circuit advancing the sequence switch of the incoming selector into the ringing position for ringing the called subscriber. Relay 240 also energizes closing a circuit from ground at its armature and front contact over the lower contact of cam 225 to battery through the left winding of relay 213. Relay 213 thereupon energizes, closing a circuit over the lower left contact of cam 214 and through the magnet winding of sequence switch 200 for advancing the sequence switch out of selection beyond position 7 into the talking position 10. As soon as the sequence switch leaves position 7, relay 213 deenergizes,

Following the completion of ringing and the response of the called subscriber, a talking circuit is established between the calling line A and the called line B over the conductors shown in heavy lines in the drawings, relay 240 being maintained energized over the talking circuit so long as the conversation continues.

When the conversation is completed and the calling subscriber restores his receiver to its switchhook the line switch 101 and the district selector 102 are released in the well known manner. Upon the release of the district selector 102, the loop circuit previously traced through the windings of relay 122, through the windings of relay 240 and to battery and ground at the incoming selector 350 is opened and relay 240 becomes deenergized. At its armature and back contact, relay 240 now establishes a circuit over the left contacts of cam 242, through the winding of relay 202 to battery at the right contact of cam 201 causing the energization of relay 202 which, at its armature and contact, establishes a circuit over the lower contact of cam 212 to battery through the left winding of relay 213. Relay 213 thereupon energizes, advancing sequence switch 200 out of position 10 into position 13 and as its left armature and front contact closes a circuit for energizing relay 207. This circuit may be traced from battery through the winding of relay 207, the left contacts of cam 229, left armature and front contact of relay 213 to ground at the left contact of cam 231. After sequence switch 200 leaves position 10, relay 213 is maintained energized over the circuit extending through its left armature and front contact, the upper contact of a cam 231, the left armature and back contact of relay 243 to ground at the lower contact of cam 228 and being energized when sequence switch 200 reaches position 13 the sequence switch is immediately driven out of position 13 through position 14 into position 16. After sequence switch 200 leaves position 15, the last traced locking circuit of relay 213 is opened at the upper contact of cam 231 but relay 213 is maintained energized over its left armature and front contact to ground at the lower left contact of cam 231 until after the sequence switch leaves position 16 and therefore when sequence switch 200 reaches position 16, it is driven into position 18 over a circuit extending through the lower contact of cam 214 and the right armature and front contact of relay 213.

With sequence switch 200 in position 18, the circuits previously traced for relays 207, 202 and 240 are opened and a circuit is established for the updrive magnet 244 for restoring the switch shaft to its normal position. The circuit for magnet 244 may be traced from battery through the winding of magnet 244 to ground through the lower contact

of cam 211. When the switch shaft reaches normal position, a circuit is closed for advancing sequence switch 200 into its normal position, which circuit may be traced from battery through the magnet winding of sequence switch 200 upper right contact of cam 214, commutator segment 245, shaft wiper 222 thence to ground at the lower right contact of cam 220. All apparatus of the office selector 250 is now in normal position and the incoming selector 350 and final selector 360 are thereupon released in the usual manner.

Overflow.

If during trunk hunting, the office selector 250 goes to an overflow position upon finding all trunks of a group busy, the shaft wiper 247 will rest upon an open portion of the overflow segment 246 and therefore, no ground potential will be connected through the test brush 230 over the back contact of relay 213 and later over the upper right contact of cam 220, as previously traced. This provision is made in order that two or more units of ten trunks each may be formed into one trunk group by grounding the overflow sleeve of the intermediate unit, leaving only the overflow sleeve of the final unit ungrounded, the final sleeve then becoming the overflow point for the entire group. The hunting movement of the selector is conducted through the intermediate points by ground encountered on such points by the test brush 230 thence over the lower right and upper left contacts of cam 229, the front contacts of the left armature of relay 213 to battery through the winding of relay 213. When the final overflow point is reached the test brush 230 encountering no ground potential, relay 213 deenergizes advancing sequence switch 200 into position 7. In position 7 a circuit is closed for relay 213 which may be traced from battery through the left winding of relay 213, the upper right contact of cam 225, commutator segment 249, shaft wiper 217 thence to ground at the lower right contact of cam 220. Relay 213 thereupon energizes advancing sequence switch 200 out of position 7 into position 10. Relay 213 deenergizes as soon as the sequence leaves position 7.

In passing through positions 8 and 9, a circuit is established for relay 243 extending through the right winding of this relay, the upper contact of cam 248, conductor 219, segment 249, shaft wiper 217 to ground at the lower right contact of cam 220. Relay 243 thereupon locks over its left winding and left armature to ground at the lower contact of cam 228, being maintained energized until the sequence switch leaves position 15. As soon as sequence switch 200 reaches position 10, the previously traced circuit for relay 213 is again estab-

lished over the upper right contact of cam 225 and relay 213 again advances sequence switch 200 out of position 10 into position 13. As sequence switch 200 passes through position 11, a circuit is established for relay 207, extending from battery through the winding of this relay, the lower left contact of cam 201, winding of relay 202, the upper right contact of cam 203, conductor 219, segment 249, shaft wiper 217 to ground at the lower right contact of cam 220. Relays 207 and 202 are thereupon locked under the control of relay 202 over the upper right contact of cam 212 until after the sequence switch leaves position 14. With relay 207 operated, when the sequence switch 200 reaches position 13, relay 233 is connected in a loop with the sender over conductors 109 and 110 in a circuit which may be traced in part from conductor 110 through the inner right armature and front contact of relay 207, the upper left and lower right contacts of cam 206, resistance element 204, relay 233, the lower contacts of cam 238 to battery, and from conductor 109 through the outer right armature and front contact of relay 207, the lower left and upper right contacts of cam 208, resistance element 210, the upper contacts of cam 235 to ground at the right armature and back contact of relay 213. The overflow relay of the sender is operated in this circuit, establishing the usual overflow condition at the sender and district selector and polarized relay 233 is operated shunting relay 202 in the manner previously described. As soon as the circuit traced from the sender through the winding of relay 233 is opened at the sender following the establishment of the overflow condition, relay 207 deenergizes, connecting the windings of relay 240 in a circuit extending back to the sender and to battery through the left contacts of cam 238 and to ground through the lower left and upper right contacts of cam 235 and the right armature and back contact of relay 213. When the district selector 102 reaches trunk closure position, relay 240 energizes, closing an operating circuit for relay 213 extending over the lower contact of cam 225, to battery through the left winding of relay 213. Relay 213 thereupon opens the circuit of relay 240 and at its right armature and front contact closes a circuit for advancing sequence switch 200 out of position 13 into position 14. With relay 240 deenergized when sequence switch 200 reaches position 14, the circuit of relay 213 is opened but this relay again energizes as soon as interrupter 251 closes its lower contact. The circuit of relay 213 may now be traced from ground through interrupter 251, lower right contact of cam 255, the right armature and contact of relay 243, the upper left contact of cam 232

to battery through the right winding of relay 213. Relay 213 upon energizing now advances sequence switch 200 into position 16.

In position 16, relay 207 is intermittently operated by the interrupter 252 over the left contacts of cam 253, intermittently connecting battery through the left contacts of cam 238 and ground through contacts of cam 235 and right armature and back contact of relay 213 for producing a flashing signal at the district link in case the connection has been established through a semi-mechanical operator's position. Relay 240 is maintained energized over the loop circuit extending to the district selector until the district selector is released, whereupon it deenergizes, closing a circuit over its armature and back contact, the left contacts of cam 242 through the winding of relay 202 to battery at the right contact of cam 201. Relay 202 energizes in this circuit, establishing a circuit over the lower contact of cam 212 for energizing relay 213, which in turn advances sequence switch 200 to the releasing position 18 in which position the incoming selector is restored as previously described.

Tell-tale.

95

Should the incoming selector go to the tell-tale position which is on the top of the bank, during any selective movement as would happen if the updrive magnet becomes stuck and fails to release, a circuit is established for sequence switch 200 over the right contacts of cam 242, tell-tale segment 254, shaft wiper 222 to ground at the lower right contact of cam 220 or upper contact of cam 216, and sequence switch 200 is thereupon advanced out of the selection position 2, 4 or 6, in which it may be standing, into position 10. The circuits of the incoming selector thereupon function as on an overflow condition except that relay 213 is energized over the contact of relay 202, which is at this time energized over the lower left and upper right contacts of cam 242, commutator segment 254, shaft wiper 222 and ground at the lower right contact of cam 220.

Release of selector upon circuit failure.

The office selector on account of faults, momentary ground or short circuits may be stuck with its sequence switch 200 in position 3 following brush selection with its shaft off normal. To guard against this condition, the interrupter 251 is provided. With sequence switch 200 in position 3, when the interrupter 251 makes its contact, a circuit is established over the lower left contact of cam 248 to battery through the right winding of relay 243 which locks over its left winding and left armature to ground.

130

at the lower contact of cam 228 until the sequence switch is advanced out of position 3. If the sequence switch 200 is still in position 3 after a period of two seconds, interrupter 251 makes its lower contact thereby establishing a circuit over the lower right contact of cam 255, the right armature and contact of relay 243, the lower right and upper left contacts of cam 253 to battery through the winding of relay 207. Relay 207 thereupon energizes and locks to ground over its left armature and left contact of cam 228 until sequence switch 200 leaves position 4. With relay 207 energized and sequence switch 200 in position 3, a circuit is established for the down drive magnet 244 which may be traced from battery through magnet 244, upper right and lower left contacts of cam 229, to ground through the left armature of relay 207 and the left contact of cam 228. When the switch shaft reaches its normal position, the sequence switch 200 is advanced out of position 3 into normal position in the usual manner. In position 3 3/4 and 4 of the sequence switch, with relay 207 energized, ground is connected to conductor 109 over the outer right armature and front contact of relay 207, the lower contacts of cam 208, resistance elements 209, 210 and the left contact of cam 211 and battery is connected to conductor 110 over the inner right armature and front contact of relay 207, the left contacts of relay 206, resistance elements 205 and 204, the lower contact of cam 203, relay 202 to battery at the right contact of cam 201. This circuit is established for transmitting an impulse of reverse current to the sender for registering the overflow condition thereat.

If the office selector is in the selection beyond position 7 and there is an open circuit on the trunk seized or the polarized relay 233 fails to function, the selector may not be advanced into the talking position 10. To guard against this, the interrupter 256 is provided which closes a circuit over the right contact of cam 248 to battery through the right winding of relay 243 as soon as the interrupter makes its left contact. Relay 243 upon energizing locks over its left armature and contact to ground at the lower contact of cam 228 until the sequence switch leaves position 7 3/4. If the sequence switch has not advanced out of position 7 3/4 fifteen seconds after relay 243 energized, interrupter 256 makes its upper contact, establishing a circuit over the left contact of cam 255, right armature and contact of relay 243, the upper left contact of cam 232 to battery through right winding of relay 213. Relay 213 thereupon energizes, advancing sequence switch 200 out of position 7 into position 10. Relay 213 upon energizing also maintains relay 243 locked between

position 7 3/4 and 9, over a circuit extending from ground through the right armature and front contact of relay 213, left contact of cam 216, left armature and front contact and left winding of relay 243, so that when sequence switch 200 reaches position 9, relay 243 is maintained locked over the lower contact of cam 228 until the sequence switch leaves position 15. As soon as the sequence switch leaves position 9, relay 213 releases since with relay 243 locked, relay 213 cannot lock itself over the upper contact of relay 231 and the left armature and back contact of relay 243 when sequence switch 200 reaches position 10. In position 10 with relay 240 deenergized, a circuit is established from ground through the armature and back contact of relay 240, left contacts of cam 242, winding of relay 202 to battery at the right contact of cam 201 for energizing relay 202 which in turn causes the energization of relay 213 and the advance of sequence switch 200 out of position 10 into position 13. From this point the circuits of the selector switch function as previously described in connection with the overflow condition.

The selector which has been advanced to position 13 by the timing interrupter 251 may find an open circuit toward the sender and cannot advance further. In this case, interrupter 251 closes a circuit over the lower right contact of cam 214 for advancing sequence switch 200 into position 14. In position 14, a circuit is thereupon established for relay 213 over the lower contact of interrupter 251, lower right contact of cam 255, right armature and contact of relay 243, relay 243 having operated upon the previous operation of interrupter 251 when the sequence switch was in position 3, then through the upper left contact of cam 232 to battery through right winding of relay 213. Relay 213 upon energizing then advances sequence switch 200 out of position 14 into position 16. In position 16, unless relay 240 has operated, relay 202 again operates, in turn operating relay 213 and advancing sequence switch 200 into releasing position 18.

Relay 240 is made sensitive in order to function in positions 7 through 10 over connections extended to relay call indicator trunks operating on 24 volts potential and therefore its springs cannot be made stiff enough to always insure release on a high resistance trunk under the overflow condition in position 16 of sequence switch 200 when 48 volts is supplied to this circuit. In position 16, therefore, the interrupter 256 is arranged to operate relay 243 over the right contact of cam 248 and 15 seconds later to close a circuit over the left contact of cam 255, right armature and contact of relay 243, the upper left contact of cam 222 to battery through the right winding of re-

lay 213 for energizing relay 213 and advancing sequence switch 200 out of position 16 into the releasing position 18.

5 Establishment of connection to call indicator office.

If the calling subscriber A initiates a connection to the line of the subscriber C in a manual call indicator office Z, the line switch 101, district selector 102 and office selector 250 function in the manner previously described up to the point where the sequence switch of the office selector advances into the selection beyond position 7, except that 15 the brushes of the office selector 250 are set to seize a trunk extending to the office Z, it being assumed that the trunk 257, 258 is at the time idle and is taken for use. At the office sender since the call is of the relay 20 call indicator class and the code registers have registered that fact upon the class switch of the sender, a circuit becomes closed for relay 125 associated with the call indicator impulser 100, which circuit may be 25 traced from battery, through the winding of relay 125, outer right armature and back contact of relay 123 to ground at the left contact of cam 126 of the control switch 114. Relay 125, upon energizing, locks over 30 its inner upper armature and contact, through cam contact 128 to ground at the right contact of cam 126, remaining locked until the impulser switch 100 leaves position 8.

35 Following the seizure of the trunk 257, 258, a control circuit is established from the sender to the control relay 313 of the trunk circuit which may be traced from battery through the right winding of relay 313, the 40 normal right contacts of relay 314, the upper left winding of repeating coil 314, the outer right back contact of relay 316, conductor 257, brush 236, the lower right and upper left contacts of cam 225, resistance element 210, the upper right and lower left contacts of cam 208, the outer right armature and front contact of relay 207, conductor 109, the upper brush of switch 102, lower contact of cam 111, wiper 112, cam contact 113, lower contact of cam 115, relay 116, winding of relay 130, right contacts of cam 118, contact of cam 119, wiper 120, lower brush of switch 102, conductor 110, the inner right armature and front contact of 45 relay 207, upper left and lower right contacts of cam 206, resistance element 204, winding of polarized relay 233, right contacts of cam 238, brush 239, conductor 258, inner armature and back contact of relay 50 316, lower left winding of repeating coil 315, normal left contacts of relay 314 to ground through the left winding of relay 313. Relay 130 and 313 energize in this circuit, the current, however, flowing in the 55 wrong direction to cause the energization

of polarized relay 233. Upon the energization of relay 130 the sender sequence switch is advanced out of position 12 in which it is standing following the completion of office group selection into position 14 in the manner fully set forth in the patent to F. A. Stearn hereinbefore referred to. In position 14 an obvious circuit is established for relay 123 over the contact of cam 124, whereupon the initial energizing circuit of relay 125 is opened. Relay 313, upon energizing, closes the circuit of relay 317 which locks over its inner right armature contact independently of relay 322 and closes an obvious circuit for the lamp 318. 70 75 80

The operator noting the illumination of lamp 318 depresses the display key 319, thereby establishing a circuit from battery at the outer right contact of sleeve relay 324, through the right winding of relay 320, the left armature and front contact of relay 317, contact of key 319, armature and back contact of relay 420 to ground at the left armature and back contact of relay 408. Relay 320 locks through both of its windings and 85 closes obvious circuits for relay 405 of the call indicator control circuit and for relay 322. Relay 322, in turn, closes a circuit for relay 323 which locks in series with relay 325. Relay 325, however, being shunted remains 90 deenergized as long as relay 317 is energized. Relay 323 at its left armature contact also closes a circuit through the windings of relays 316 and 420 in series, relay 316 disconnecting the windings of relay 313 100 from trunk conductors 257 and 258 and connecting these trunk conductors to the impulse leads 331 and 332 extending to the indicator control circuit. With relay 313 disconnected and deenergized, the circuit of relay 317 is opened, removing the shunt from around the winding of relay 325 which thereupon energizes in the locking circuit of relay 323. At its back contact 105 relay 317 connects the lamp 318 in series with the interrupter 326 for flashing the lamp until the display of the wanted line number is completed on the call indicator and the operator in response thereto has extended the connection to the wanted line. 110 At the indicator control circuit upon the energization of relay 405 ground is connected to the conductor 406 for furnishing operating and locking ground potential to the several control and registering relays 115 of the call indicator. 120

At the office sender when relay 316 energized and opened the circuit previously traced through the windings of relays 313 and 130, relay 130 deenergized thereby completing a circuit over its right armature and back contact, through the inner right armature and front contact of relay 123, contacts of cam 128 to battery, through the winding of relay 127. Relay 127 thereupon 125 130

energizes closing a circuit from ground over its armature contact, the lowermost armature and front contact of relay 125, contact of cam 129 to battery through the 5 magnet winding of the impulser switch 100 for advancing the impulser switch out of position 1, through position 8. As soon as the switch 100 leaves position 8 the locking circuit of relay 125 is opened so that when 10 switch 100 rotates around into position 1, it finds no operating circuit and is arrested after completing a single revolution. When passing through a complete revolution 15 switch 100 transmits a plurality of series of code impulses to the call indicator of Fig. 4 in the well-known manner, a series being transmitted for each digit of the line designation. With relay 123 energized and relay 130 deenergized, the circuit over 20 which the code impulses are transmitted may be traced from conductor 133, upper armature and front contact of relay 125 or the contact cam 135, inner left armature and back contact of relay 130, inner left armature 25 and front contact of relay 123, upper contact of cam 115, contact of cam 113, thence as previously traced to conductor 257, outer armature and front contact of relay 316, conductor 332, inner right armature and 30 back contact of relay 410, winding of positively polarized relay 400, winding of negatively polarized relay 401, winding of marginal relay 402, outer left armature and back contact of relay 410, conductor 331, 35 inner armature and front contact of relay 316, conductor 258, thence as previously traced to wiper 120, contact of cam 119, outer left armature and contact of relay 123, outer left armature and back contact 40 of relay 130, inner lower armature and contact of relay 125 or the upper contact of cam 136, to conductor 134. The impulses of each series may consist, in the usual manner, of light positive and light 45 and heavy negative impulses.

Since all of the positive impulses are light, the marginal polarized relay 233 which is included in the impulser circuit does not respond. In response to impulses 50 of each series relays 400, 401 and 402 selectively operate and in conjunction with relays 403 and 404 cause the operation of the usual recording relays (not shown). In the well-known manner the pairs of transfer 55 relays such as 411, 412, 413, 414, 415, 416, 417, 410, 427 operate upon the transmission of successive series of impulses until relay 427 operates upon the transmission of the last series of impulses. When relay 427 60 operates it locks to conductor 406 in series with relay 410, but relay 410 does not operate in this locking circuit until the completion of the last series of impulses. When the last series of impulses is terminated 65 and relays 403 and 404 both become

deenergized, relay 410 operates opening the previously traced impulser circuit through the windings of relays 400, 401 and 402, closing a new circuit extending from conductor 322, over the inner right armature and front 70 contact of relay 410, winding of negatively polarized relay 401, conductor 418, outer left armature and front contact of relay 410 to conductor 331. It is to be noted that the operation of relay 410 has been instrumental in cutting relays 400 and 402 from the pulsing circuit, over conductors 331 and 332 for reducing the resistance of this circuit and in reversing relay 401 in the circuit 75 so that it will respond to a positive impulse. The resistance of the circuit is additionally reduced by the connection of resistance 419 in parallel with relay 401 through front contacts of relay 410. At the sender upon the completion of the transmission of the code 80 impulses and the return of switch 100 to position 1, a circuit was closed for translator control sequence switch 114 for advancing it out of position 9, the circuit extending over the contact of cam 137, contact 85 of cam 139, lowermost armature and back contact of relay 125 to ground at the armature and front contact of relay 127. As the switch 114 advances from position 9 through position 9½, a circuit is closed for 90 transmitting a heavy impulse of positive current over the impulser circuit previously traced through the winding of relay 233 and the winding of polarized relay 401. At the sender this current flows from battery 95 over cam contact 138, cam contacts 140, the upper armature and back contact of relay 125, thence over the circuit traced through the windings of relays 401, and 233 returning over the lowermost contact of cam 136 100 to ground at the right contact of cam 126. Relay 401 energizes closing a circuit from ground on conductor 406, through the contact of relay 401, inner left armature and front contact of relay 410 to battery through 105 the winding of relay 421. Relay 421 thereupon closes a circuit from ground at the outer contact of relay 417, which relay energized during the transmission of the tens 110 series of code impulses, the outer right armature and contact of relay 427, left armature and contact of relay 421, winding of relay 408 to battery through the winding of relay 421. As soon as the heavy positive impulse through relay 401 ceases, relay 408 115 energizes in the locking circuit of relay 421 opening at its right armature and back contact the circuit of relay 316. Relay 316 thereupon deenergizes, disconnecting the impulse leads 331 and 332 from the trunk 120 conductors 257 and 258 connecting these trunk conductors to the windings of relay 313. Upon the transmission of the heavy 125 positive impulse to the relay 401, relay 233 receives current in the proper direction and 130

of sufficient strength to cause its energization, whereupon sequence switch 200 of the office selector 250 is advanced into the talking position 10 as previously described. The 5 sender is advanced to the talking selection position following the transmission of the heavy positive impulse, in turn advancing the district selector to the talking position and itself becoming disconnected from the 10 established connection and restored to normal condition. As soon as the subscriber's line is cut through to the office Z, relay 313 again energizes closing a locking circuit for relay 325 and shunting down relay 323. 15 The operator noting the display of the wanted line number upon the lamps of the indicator inserts the plug 327 in which the trunk circuit terminates, in the jack 328 of the indicated line, whereupon relay 324 energizes, opening the holding circuit of relay 320, which in turn, opens the circuits of 20 relays 322 and 405. Relay 322 functions to disconnect the lamp 318 from the interrupter 326, and relay 405 removes ground potential from the conductor 406, permitting 25 the restoration of all operated equipment of the call indicator. The apparatus at the office Z then functions in the usual manner to call the wanted subscriber and to 30 control supervision upon the subscriber's response and following the termination of the conversation. Upon the completion of the conversation between lines A and C the line switch 101, district selector 102 and office 35 selector 250 are released in the manner previously described, and the operator at office Z receiving the usual disconnect signal displayed on lamp 329, removes plug 327 from the jack 328, thereby releasing the apparatus 40 at her position.

Had the call been established to the office Z from the office W, over an office selector of the three-wire type, such as disclosed in the aforementioned patent to F. A. Stearn, 45 no heavy positive impulse would be required to advance the office selector to the talking position and, therefore, the sender at such office would not be equipped to transmit such a positive impulse following the completion 50 of the transmission of call indicator impulses. In this case following the registration of all call indicator impulses at the call indicator of office Z and the energization of relays 410 and 427, relay 408 is automatically 55 energized through the operation of timing relays 422 and 423 for disconnecting the indicator from the trunk circuit through the operation of relay 316. Relays 422 and 423 function in the following manner. When relay 417 energizes during the transmission of the tens series of impulses, a circuit is established over its contact, the left armature contact of relay 423 to battery through the winding of relay 422 and relay 422 energizes. During 60 the transmission of the units series of 65

impulses relay 427 energizes closing a circuit from ground at the contact of relay 417, through the outer right contact of relay 427 to battery, through the winding of relay 423. Relay 423 energizes, opening the circuit 70 through relay 422. After an interval measured by the releasing time of slow releasing relay 422, a circuit is established from ground at the back contact of relay 422, the right contact of relay 423, windings of relay 408 and 421 to battery. Relay 408 thereupon energizes opening the circuit of relay 316 disconnecting the call indicator control circuit from trunk conductors 257 and 258. The interval measured by the 80 timing relays 422 and 423 is designed to delay the disconnection of the call indicator control circuit from trunk 257, 258 for a period sufficient for the reception of a heavy positive pulse where one is required. 85

What is claimed is:

1. In a telephone exchange system, a trunk, a selector switch for extending a connection therefrom, control means for said switch, a control circuit extending thereto over said trunk, means for further extending said connection, means at said switch for disassociating said control circuit from said control means and for extending it to said connection extending means, and means at 90 said switch for compensating the resistance of said control circuit incident to the extension of said circuit.

2. In a telephone exchange system, a trunk, a selector switch for extending a connection therefrom, control means for said switch, a control circuit extending thereto, over said trunk means for further extending said connection, means at said switch for disassociating said control circuit from said control means and for extending it to said connection extending means, resistance elements, and means for variably connecting said elements into said control circuit for compensating the resistance thereof during 100 the connection thereof to said control means and to said connection extending means. 105

3. In a telephone exchange system, a trunk, a selector switch having a plurality of stages of operation, means for extending a connection over said trunk to said switch, means for operating said switch in certain of its stages to further extend said connection, other connection extending means controllable over said trunk in another stage of operation of said switch, resistance elements, and means at said switch for variably connecting said elements into said trunk in different stages of operation of said switch. 115

4. In a telephone exchange system, a trunk, a selector switch, means for extending a connection over the trunk to said switch, an auxiliary switch having a series of positions for controlling said selector switch in its operation, means for operating the switch 125 130

- in certain positions of said auxiliary switch to further extend said connection, other connection extending means controllable over said trunk in a certain position of said auxiliary switch, resistance elements, and means controlled by said auxiliary switch for variably connecting said elements into said trunk in different positions of said auxiliary switch. 65
5. In a telephone exchange system, a selector switch for extending talking connections, two conductor trunks extending thereto and therefrom, means for further extending said connections, controlling mechanism for said switch arranged to be sequentially advanced through successive positions in the operation of said switch, and means controllable over said two conductor trunks serially incident to the operation of said connection 70 extending means for advancing said mechanism to a given position. 75
6. In a telephone exchange system, a selector switch for extending talking connections, two conductor trunks extending thereto and therefrom, means for further extending said connections, controlling mechanism for said switch arranged to be sequentially advanced through successive positions in the operation of said switch and to rest in a given position 80 during the control of said connection extending means; and means controllable over said two conductor trunks serially incident to the operation of said connection extending means for advancing said mechanism to a position in which the talking circuit is established through said switch. 85
7. In a telephone exchange system, a selector switch for extending talking connections, two conductor trunks extending thereto and therefrom, means for further extending said connections, controlling mechanism for said switch arranged to be sequentially advanced through successive positions in the operation of said switch and to rest in a given position 90 during the control of said connection extending means, and a polarized relay controllable over said two conductor trunks incident to the operation of said connection extending means for advancing said mechanism to a position in which a talking circuit is established at said switch. 95
8. In a telephone exchange system, a selector switch for extending talking connections, two conductor trunks extending thereto and therefrom, means for further extending said connections, controlling mechanism for said switch arranged to be sequentially advanced through successive positions in the operation of said switch and to rest in a given position 100 during the control of said connection extending means. 105
9. In a telephone exchange system, a selector switch for extending talking connections, two conductor trunks extending thereto and therefrom, means for further extending said connections, controlling mechanism for said switch arranged to be sequentially advanced through successive positions in the operation of said switch and to rest in a given position 110 during the operation of said switch and to rest in a given position during the operation of said connection extending means, a polarized relay at said switch arranged for insertion in series relation with said trunks in said given position of said mechanism, means for transmitting a heavy pulse of current of the proper polarity for operating said relay to establish a talking circuit at said switch, and a second relay included serially in said talking circuit for controlling the further advance of said mechanism. 115
10. In a telephone exchange system, a selector switch for extending talking connections, two conductor trunks extending thereto and therefrom, means for further extending said connection, controlling mechanism for said switch arranged to be sequentially advanced through successive positions in the operation of said switch and to rest in a given position during the operation of said connection extending means, a polarized relay at said switch arranged for insertion in series relation with said trunks in said given position of said mechanism and irresponsive to connection controlling impulses transmitted therethrough, a sender for controlling the operation of said switch and said connection extending means, and means at said sender operative upon the completion of its control of the extension of said connection for transmitting an impulse of current of proper polarity for operating said relay, whereby said mechanism is advanced to establish a talking circuit at said switch. 120
11. In a telephone exchange system, a selector switch for extending talking connections, two conductor trunks extending thereto and therefrom, and means controllable over said trunks serially for further extending said connections. 125

In witness whereof, I hereunto subscribe my name this 9th day of August A. D., 1923.

LEWIS H. JOHNSON.
